UNITED STATES PATENT OFFICE.

HENRY O. HAVEMEYER, JR., OF NEW YORK, N. Y.

RAILWAY-TRACK CONSTRUCTION.

Application filed December 29, 1925. Serial No. 78,230.

The present invention pertains to railway track construction and more particularly to means employed in connection with the termini of tracks arranged upon relatively 5 movable structures or elements, such as barges, turntables, floats and the like, whereby a car may, without fear of derailment owing to the non-alignment of the rail ends, be safely passed over, or along the track, or, 10 more specifically, from one track-way to another.

I am aware that such means, broadly considered, has heretofore been proposed, but the present invention possesses certain advantages not to be found in the older structures so far as I am advised. Under the present arrangement, the rails, which are of ordinary construction, extend to the end of the structure upon which they are laid and the re-railing means are secured directly to the rails rather than to the rail supporting structure. Furthermore, the construction of the parts which are associated with the rail ends is such that the rails of various track-ways may be brought into close relation, a point of manifest advantage as when, for instance, the structure is employed in connection with a turntable.

The invention is illustrated in the annexed drawings in connection with two track-ways and in

Figure 1 the termini of the tracks upon two relatively shiftable elements are shown in plan with my re-railing device applied thereto,

Figure 2 is a cross sectional view taken on the line II—II of Figure 1 looking in the direction of the arrow,

Figures 3, 4 and 5 are detail sectional views taken on the line III—III, IV—IV and V—V, respectively, of Figure 1,

Figure 6 is a perspective view of one of the wheel engaging and shifting elements, and

Figure 7 is a similar view of one of the wheel supporting or bearing blocks which cooperates with one of the wheels while the shifting and engaging element is acting to shift the wheels laterally as the vehicle or car is being moved along the track-way.

It is of course to be understood that the invention is applicable to a large number of trackways where such ways have to be closely associated as, for instance, those leading up to a turntable, but for the purpose of description I have illustrated the same in con-

nexion with two adjacent converging track-ways as shown in Figures 1 and 2.

Referring to Figure 1, 1 denotes a float bridge having two pairs of rails 2 and 3, 60 and 4 and 5 forming respectively two track-ways.

The rails are of the usual or standard type and their ends terminate flush or substantially so, with the end of the float bridge. 65 Similar rails 2^a and 3^a, and 4^a and 5^a form corresponding track-ways secured on a movable body, say a car float denoted by 1^a, Figure 1.

The rails extend to the end of the car 70 float as with those on 1 and are likewise of standard formation.

As shown in Figure 1 the ends of the trackways are out of alignment, that is to say the car float cannot be, or has not been, 75 brought to such position that the adjacent ends of the rails produce an uninterrupted or continuous way.

To provide means whereby a car may 80 safely pass along the track-ways I employ two elements located and secured to the rails at or adjacent the ends thereof.

Such elements may be termed a re-railer or shifter and an associated rail head extension or bearing block. Inasmuch as the 85 re-railers are alike in form, a description of one will suffice. The same is true of the rail head extension bearing block.

Referring more specifically to Figs. 3 to 6, the re-railing element comprises a body 6 90 formed along one face or side at its base, with a lateral extension 7 of such contour as to fit between the under face of the rail head and the upper face of the rail base.

The body at its outer portion extends upwardly as 8 to a point a substantial distance above the tread surface of the rail head and the inner face of such upward extension (or that face which lies toward the rail) is formed on an incline or, in other words, is 95 formed with an inclined face 9 the lower edge or margin whereof terminates at the upper portion of a groove or channel 10 extending longitudinally of the member. As will be seen upon reference to the sectional views, the inner side of the channel aligns 100 with the adjacent side face of the rail head.

As will be most clearly seen upon reference to Figures 1 and 6 the groove or channel 10 is widened out at each end and the 110 inclined face 9 follows the contour of the groove so that the end portions denoted by

9^a and 9^b of said face stand further away from the rail than does the central portion. As will be seen, section 9^a of the inclined or beveled face is inclined outwardly to a greater degree, more nearly to the horizontal than is the central portion, the two sections merging into each other on easy lines to prevent shock in the use of the device. The widening of the mouth of the groove at the entrance end thereof and the gradual increase of pitch toward the vertical of the inclined face from the rail ends inwardly ensures absence of jar or, in other words, ease of operation.

15 Associated with the re-railing element as above described, is what I term a rail head extension. It takes the form of a block of the contour best shown in Figure 7 comprising a body portion 11 having upon its inner face a rib or extension 12 adapted to fit between the under face of the rail head and the upper face of the rail base. The height of the block is such that its upper face 13 lies flush with the tread surface of the rail when the parts are assembled. The side face of the extension block may be tapered off as at 14 to lighten the same.

20 The elements when placed in position upon opposite sides of the rail at its end are secured in place by bolts 15.

25 In operation, and assuming that a car is moving on the tracks 4 and 5 in the direction of the arrow, Figure 1, the flange of the wheel 16 running on rail 5 will contact face 9^a of the re-railing element secured to rail 5^a and, by reason of the inclination of said face, will act to force the wheel laterally into alignment with rail 5^a. At the same time the flange on the other wheel 17 will ride upon and along the rail head extension block 13 secured to rail 4^a and as such member is smooth the wheel will roll thereover and at the same time be shifted laterally without undue strain.

40 45 The gradual increased pitch (toward the vertical) of the inclined portions 9^a and 9^b serves to gradually shift the wheels laterally until they align with the tracks 4^a and 5^a over and upon which they may then pass.

50 55 By spacing and inclining the face 9^b from the track and widening the groove 10 at such point the wheel flanges may readily enter the latter without jar or impact.

60 While I have shown the devices as applied to the rail ends upon both of the abutting structures their presence is not necessary upon both but where there is one-way traffic only the re-railing and supporting blocks need be present on but one set of rail ends.

What is claimed is:

1. In combination with a pair of rails forming a track-way, means located at the end of each rail for laterally shifting a wheel passing from a non-aligning adjacent track-way onto the rails of said first named

track-way, said means comprising a grooved block having an upstanding member spaced from the rail presenting an inclined face adapted to contact the flange of an advancing wheel and to force the wheel laterally, and a block secured to the opposite side of the rail, the upper face of the block being in substantial alignment with the tread surface of the rail.

2. In combination with a pair of rails; a re-railing means comprising a block secured to the outer side of each rail, the upper face of said block being in substantial alignment with the tread surface of the rail, and a second member secured to the opposite face of each rail, said member presenting a groove or channel adjacent the head of the rail, which groove widens out toward its outer end, and an upstanding member spaced away from the rail, and having that face which faces the rail inclined outwardly from the vertical.

3. In combination with a pair of rails; a re-railing means comprising a block secured to the outer side of each rail, the upper face of said block being in substantial alignment with the tread surface of the rail, and a second member secured to the opposite face of each rail, said member presenting a groove or channel adjacent the head of the rail, which groove widens out toward each end, and an upstanding member spaced away from the rail, and having that face which faces the rail inclined outwardly from the vertical.

4. In combination with a pair of rails; a re-railing means comprising a block secured to the outer side of each rail, the upper face of said block being in substantial alignment with the tread surface of the rail, and a second member secured to the opposite face of each rail, said member presenting a groove or channel adjacent the head of the rail, which groove widens out toward its outer end, and an upstanding member spaced away from the rail, and having that face which faces the rail inclined outwardly from the vertical, said inclination decreasing from the outer end of the member inwardly thereof.

5. In combination with a pair of rails forming the termini of a track-way; means for shifting the wheels of a vehicle from a non-aligning track-way onto said rails, said means comprising a member secured to the inner face of one rail at its end, provided with means to engage the flange of an oncoming wheel and to cam the wheel laterally onto the rail, and a block secured to the outer face of the second rail adjacent its end, the upper face of said block lying in the plane of the tread of the rail and forming in effect a lateral rail head extension.

6. In combination with a pair of non-aligning rails; a re-railing means comprising

ing a block secured to the outer side of at least one of said rails, the upper face of said block being in substantial alignment with the tread surface of the rail; and a second member secured to the opposite face of said rail, said member presenting a groove or channel adjacent the head of the rail, which groove widens out toward the end of

the rail, and an upstanding member spaced away from the rail and having that face ¹⁰ which faces the rail inclined outwardly from the vertical.

In testimony whereof I have signed my name to this specification.

HENRY O. HAVEMEYER, JR.
